WILD BIRD SUET CAKE COMBINED CONTAINER AND FEEDER

Richard G. Willard, Wethersfield, Conn.

Application January 30, 1957, Serial No. 44,663

Term of patent 7 years

(Cl. D31—2)

FIG. 2

Fig. 1 is a perspective view of a wild bird suet cake combined container and feeder showing my new design with the dowel perch under the top lid, the rear being substantially plain; and

Fig. 2 is a view similar to that shown in Fig. 1 but in position for use.

I claim:

The ornamental design for a wild bird suet cake combined container and feeder, substantially as shown and described.
